UNITED STATES PATENT OFFICE.

WINFIELD E. HINSDALE, OF TRENTON, NEW JERSEY, ASSIGNOR TO TRENTON POT-
TERIES COMPANY, OF TRENTON, NEW JERSEY, A CORPORATION OF NEW JERSEY.

WATER-CLOSET.

1,391,475.

Specification of Letters Patent. Patented Sept. 20, 1921.

Application filed July 17, 1917. Serial No. 181,069.

To all whom it may concern:

Be it known that I, WINFIELD E. HINSDALE, a citizen of the United States, residing at Trenton, in the county of Mercer and 5 State of New Jersey, have invented a certain new and useful Improvement in Water-Closets, of which the following is a specification.

My present invention pertains to improvements in water-closets, and more especially 10 to closets of the siphon jet type.

The invention is directed particularly to improvements in existing types of siphon jet water-closets, and has for one of its objects the incorporation, integrally with the bowl and general closet structure, of a vent duct of large area and, at the same time, to retain a symmetrical shape and to avoid distortion of the complete closet by the incorporated chambers and water-ways or passages.

In designing such a structure, it should be borne in mind that certain features in common use, such as the means provided for 25 attaching the seat, have become more or less staple or standardized, and the fact that makers of special seats have adopted certain and fixed measurements makes it imperative that such a design conform to the trade 30 requirements in order to obviate the necessity of providing special trimmings and consequently enhancing the cost thereof.

Furthermore, it is desirable, if in fact not necessary, that little, if any, departure be 35 made from what has grown, by years of use and the practice of all makers, to be the standard measurement of a closet, both as to height and width.

A still further object of the invention re- 40 sides in the provision of special ways for the introduction of the water into the flushing rim and to the jet opening; also in the provision of special water ducts or openings for flushing the walls of the vent duct.

45 The arrangement of the channels or conduits which convey the water to the flushing rim is such that all the contained air in the water passages or conduits above the water-level in the bowl will be driven ahead 50 of the falling water from the flushing device, without in any way mixing said confined air with the following or advancing

water, thus eliminating all noise caused by the mixing of air and water under pressure.

It is evident from what has been said that 55 in order to bring about the introduction of a vent duct and the necessary water ways or channels within the confines of a standard closet, changes must be made in the water ways, both as to inlet and outlet, and 60 that the vent duct itself must be kept below the plane of the rim of the bowl until well clear of the portion of the closet that is intimate to the user.

Two embodiments of the invention are disclosed in the annexed drawings, wherein:

Figure 1 is a vertical sectional view of the closet having a local or rear vent of large area;

Fig. 2 a vertical sectional view, the plane 70 of section at the left being on the line I—I, and that to the right being on the line II—II of Fig. 1;

Fig. 3 a sectional plan view, the section being on the line III—III of Fig. 1; 75

Fig. 4 a vertical sectional view, showing a modified arrangement wherein the vent duct is omitted, but the other features are retained; and

Fig. 5 a transverse detail sectional view, 80 on the line V—V of Fig. 4.

Referring first to Figs. 1 to 3 inclusive, it will be seen that the closet is formed as a one-piece structure, with the various ducts and water-ways therein.

85 The bowl proper is denoted generally by 1, and surmounts a base or pedestal 2. The vent duct is designated by 3, the inner portion whereof opens directly into the bowl, said inner portion lying below the upper 90 face of the bowl (denoted by 4) and terminating between the separated rear ends of the flushing rim 5. Said rim, as will be noted upon reference to Figs. 1 and 3 (see also Fig. 5) is not continuous and the space 95 between its ends is bridged over by a curved and receding lip 6, which is not as deep as the rim, but merges into the same. By omitting the usual flushing rim for a space of approximately four inches at the rear of 100 the bowl and providing the receding lip or rim portion 6, formed upon an easy curve, I secure an anti-soiling feature, by increasing the length of the bowl-top to the rear by

over an inch, thus removing this portion of foulable surface in its entirety.

To the rear of the seat hinge-post holes 7, duct 3 extends upwardly and rearwardly, terminating in a mouth or spigot 8. Pockets 9 are provided in the side walls of the closet, or the vent duct, beneath the holes 7, which pockets, while enlarging the vent duct, also afford a ready means for securing the nuts 10 upon the inner ends of the seat hinge-posts. Furthermore, the retaining nuts will be enclosed, thus eliminating the usual and unsightly bolts and nuts as they appear under the regular exposed seat wings of the standard closet of today.

It will thus be seen that I have provided a vent duct of maximum area, and one which is open and free throughout its length between the bowl and the stack to which it is connected. Such an arrangement of the vent duct, and the omission of the usual rear portion of the flushing rim 5 necessitates a rearrangement of the water ducts and passages.

25 The water supply from the usual tank or reservoir enters the regular top inlet or conduit 10, from which extend branches or ways 11, which pass downwardly and slightly forward and open inwardly into a chamber 30 or recess 12 underlying the bottom of the trap and provided with the usual jet orifice or opening 13. Each of the vertically-disposed ways 11 is in communication with a horizontally-disposed way 14, the forward 35 end of which turns upwardly, as at 15, and opens into the adjacent rear end of the flushing rim 5.

A plurality of openings 16 will preferably be provided through the wall between 40 the upper portion of the vent 3 and the conduit 10, to thoroughly flush or wash down the walls of the vent duct at each operation of the closet.

The trap and siphon outlet of the closet 45 are denoted by 17 and 18, which latter terminates in the usual outlet nozzle 19.

From the foregoing it is thought that the advantages accruing from the construction will appear to those skilled in the art, but it 50 may be well to set them forth in a general way.

Heretofore, vent ducts have been made integral with the closet and connected to the bowl by means of one or more openings extending through the bowl wall and under the edge of the continuous flushing rim, producing an uncleanable pocket back of the bowl surface and out of reach of the flushing water.

60 With the construction above set forth I am enabled to provide a local or rear vent which has a clear and free opening extending from the bowl to the stack and which in a closet of standard dimensions may be of full four-inch diameter. Furthermore, the

duct is kept below the rim of the closet bowl until well beyond the point of seat attachment, thus taking the rear raised portion of the vent well out of the way of the user.

So, too, as above noted, the cutting away 70 of the flushing rim at the rear is of marked advantage, for reasons above set forth, and besides allows free access to the vent duct for the purpose of placement of the nuts employed to hold the seat hinge posts in 75 place, as well as for cleaning purposes.

Also, by reason of the placing of the bowl outlet passage or trap farther to the rear than usual, I secure a greater volume of 80 water in the bowl and trap and a proportionally greater resistance to the passage of sewer gas.

When no local vent exists or is needed, the vent duct may be omitted, and the other structural features and their inherent advantages retained. Such a construction is disclosed in Figs. 4 and 5, and inasmuch as the vent duct is alone omitted the other parts are denoted by the same reference numerals as in the other figures.

90 The cut-away sanitary rim, the covered seat post boxes or pockets, and the above water-level feed to the rear ends of the flushing rim are all present. The receded rear portion of the bowl surface, denoted by 95 20, which extends up to the pockets or boxes 9, is washed down by the water passing from the openings 16, as under the other construction.

100 While the design of a closet around the novel features which I have introduced seemingly admits of but little change, still it is evident that closets of types other than of the siphon jet class may be similarly produced, and I do not, therefore, wish to be 105 understood as limiting myself thereto.

Having thus described my invention, what I claim is:

1. In a water-closet, the combination of a bowl; a flushing rim extending along the 110 sides and forward portion only of the bowl, said flushing rim being supplied from below through ducts on either side of the bowl from the proximate ends of the rim to the main water ducts and entirely above the 115 water level in the bowl; a lip bridging the space between the proximate ends of the rim, said lip being relatively shallow; and a vent duct opening directly into the bowl below the lip and in rear thereof said duct and its 120 inner end lying below the upper face of the bowl proper and its outlet end entirely above the plane of the bowl rim.

2. In a water-closet, the combination of a bowl; and a vent duct extending rearwardly 125 therefrom, said duct having a pocket opening toward the vent passage and accessible from the interior of the bowl formed in each of the side walls thereof for the reception of the inner ends of the seat hinge posts and 130

the nuts employed in securing the same in place.

3. In a water-closet, the combination of a bowl; a flushing rim therefor, said rim terminating short of the rear of the bowl at each side thereof; a vent duct opening into the bowl between the ends of the rim; and a pocket opening toward the vent passage and reached from the interior of the bowl 10 through the duct formed in each of the side walls of the duct, the upper wall of each pocket having an opening therein for the reception of the seat hinge post.

4. In a water-closet, the combination of a bowl; a flushing rim therefor, the upper surface of the bowl extending horizontally for a space to the rear of the bowl opening and the rim; and a vent duct opening directly into the bowl and underlying at its inner end 20 said horizontal extension; and a pocket formed in each of the side walls of the duct and likewise underlying said extension, said pockets each having an opening extending into the same for the reception of the seat hinge posts.

5. In a water-closet, the combination of a bowl; a flushing rim therefor, the ends whereof are separated and terminate adjacent the rear portion of the bowl at the sides 30 thereof; a vent duct extending rearwardly from the bowl and opening into the same between the ends of the rim, said duct forward of the point of seat attachment lying entirely below the upper face of the bowl and entirely 35 above the plane of the bowl rim at its outlet end; a series of water jets opening into the upper portion of the duct; and water conduits entirely above the water level in the bowl, said conduits on either side of 40 the bowl and between the main water ducts and the ends of the flushing rim opening into the rim from below adjacent each end thereof.

6. In a water-closet, the combination of a bowl; an underlying trap and siphon; a flushing rim for the bowl, said rim extending along the sides and forward portion only of the bowl; a vent duct of large area 45 extending rearwardly from the rear portion of the bowl and above the trap and siphon presenting a free, unobstructed and undiminished passage throughout its length, with no portion of the vent passage or structure above the rim of the bowl forward of 50 the seat attachment and entirely above the plane of the rim at its outlet; a water inlet above the duct; jet openings extending therefrom through the upper wall of the duct; branch conduits extending from the inlet 55 downwardly to each side of the duct and terminating in a siphon jet chamber; and a lateral conduit extending from each branch conduit horizontally on either side of the closet, wholly above the water level in the 60 bowl and below the flushing rim and com-

municating with the flushing rim, from below, at its ends.

7. In a water-closet, the combination of a flushing rim cut away at its rear and fed from below at its rear ends from horizontal 70 water ways integral with the closet structure and entirely above the water level in the bowl and entirely below the flushing rim; a large vent duct or passage disposed between the outlet or trap way of the bowl 75 and the cut-away flushing rim, wholly below the top of the closet forward of the point of seat attachment and entirely above the top plane of the closet at its outlet end; and means for flushing the inner walls of the 80 vent duct from the inlet water-way.

8. In a water-closet, the combination of a bowl; a flushing rim cut away at its rear and fed from below at its rear ends from horizontal water-ways integral with the 85 closet structure and entirely above the water-level in the bowl and entirely below the flushing rim; a vent duct or passage of large area disposed between the outlet or trap way of the bowl and the cut away flush- 90 ing rim, and wholly below the top of the closet forward of the point of seat attachment; means for flushing the inner walls of the vent duct from the inlet water-way; and pockets closed as to outside appearance on 95 either side of the vent duct to receive seat bolts.

9. In combination with a water-closet bowl; a flushing rim; a seat attaching means to the rear of the bowl wholly inside 100 the outer walls of the closet structure, perforated from the top only to receive hinge locking means and accessible through a cut-away rear portion of the adjacent portion of the closet bowl and flushing rim; and 105 means for washing the exposed inner surface.

10. In a water-closet, the combination of a bowl; a flushing rim cut away at its rear and fed from below at its ends, from below 110 its own level, on either side of the closet through a horizontally disposed water passage integral with the closet structure and entirely above the water-level in the bowl and below the flushing rim; a local vent 115 duct originating in the bowl entirely under the cut-away portion of the flushing rim and terminating at the extreme rear of the closet entirely above the top of the flushing rim, with no part of its structure above the 120 rim forward of the point of seat attachment; and means for washing the exposed inner surface of the vent duct.

11. In a water-closet, the combination of a bowl; a flushing rim; a seat attaching 125 means to the rear of the bowl; wholly inside the outer walls of the closet structure, perforated from the top only to receive hinge locking means and accessible through a cut-away rear portion of the flushing rim and 130

a recessed adjacent portion of the closet bowl; a vent duct originating in the bowl entirely under the cut-away portion of the flushing rim and terminating at the extreme rear of the closet entirely above the top of the flushing rim, with no part of the vent duct structure above the rim of the bowl

forward of the point of seat attachment; and means for washing the interior surface of the vent duct.

In testimony whereof I have signed my name to this specification.

WINFIELD E. HINSDALE.
